BROOM AND THE LIKE

Walter Trillia Cassels, Buenos Aires, Argentina

Application January 2, 1935, Serial No. 145

3 Claims. (Cl. 15—159)

The invention relates to improvements in broom manufacture, to secure the straw, fiber or hair in a new way, the objects of the improvements being to obtain:

- 5 1st. Easier handwork.
- 2nd. Quicker production.
- 3rd. Cheaper transport,
- 4th. Greater durability,
- 5th. Lighter weight.

10 6th. Economical renewal.

One form of the invention is illustrated in the accompanying drawing, in which Figures 1 and 3 are side views of a broom, Figures 2 and 4, plans of the same; and Fig. 5 elevation of a broom handle, Figs. 1 and 2 showing the parts as first put together while 3 and 4 show them when pressed and trimmed. These parts are as follows:—

20 A, bundles of straw, fibre or hair, of which one end is placed with cement in the hoops B, fastened on opposite sides of a ferrule C, made slightly conical to hold the end likewise conical, of a pole D (Figure 5). Extending from the hoops and embracing the straw, fibre or hair, are the 25 yokes E, which, where they cross each other, are clasped with the link F.

In the manufacture, hoops B and ferrule C can be formed together with rivet or spot-weld joints. One end of the straw fibre or hair, after treating 30 with cement, is put into the hoops as shown in Figures 1 and 2, and then squeezed flat in a press, so that the material is tightened into the lesser oblong space of Figures 3 and 4, which also show the free ends of the straw, etc. cut to an even 35 length, and any excess above the hoops, trimmed off. Rivets or nails may be used to further bind the hoops to the material enclosed.

The yokes E have their free, bent ends pushed into holes G in the hoops, said yokes being tight-

ened at the centre, where they cross each other, by a link F. The pole is left loose, to be put on by the user, as its conical end readily fits firmly into the ferrule without nail or screw, yet can be pulled out to use again in a new broom body when the old one wears out.

I am aware that prior to my invention, brooms have been made with material stuck into a metal holder, and therefore do not claim such a combination broadly, but I do claim:

1. A broom comprising a pair of interengaging hoops, bundles of broom material having their head portions clasped by said hoops, means securing the head portions of said bundles in said hoops consisting of cement, the interengaging 15 portions of said hoops forming a conical socket adapted to receive a broom handle.

2. A broom comprising a pair of interengaging hoops, bundles of broom material having their head portions clasped by said hoops, means securing the head portions of said bundles in said hoops consisting of cement, yokes fastened in said hoops and embracing the bundles below the hoops and a central tightening link for the yokes, the interengaging portions of said hoops forming a 25 conical socket adapted to receive a broom handle.

3. A broom comprising a pair of interengaging hoops, bundles of broom material having their head portions clasped by said hoops, means securing the head portions of said bundles in said hoops 30 consisting of cement, rivets through the hoops and said head portions, yokes fastened in said hoops and embracing the bundles below the hoops and a central tightening link for the yokes, the interengaging portions of said hoops forming a conical 35 socket adapted to receive a broom handle, and said rivets adapted to retain the hoops in substantially flattened position.

WALTER TRILLIA CASSELS.
